UNITED STATES PATENT OFFICE.

WALTHER GLOOR AND LOUIS HAACK, OF NEW YORK, N. Y.

CARPET-ATTACHMENT DEVICE.

1,381,913.

Specification of Letters Patent. Patented June 21, 1921.

Application filed March 8, 1921. Serial No. 450,592.

To all whom it may concern:

Be it known that we, WALTHER GLOOR and LOUIS HAACK, the former a citizen of the Republic of Switzerland and the latter a citizen of the United States of America, both residing at New York, in the county of New York and State of New York, have invented certain new and useful Improvements in Carpet-Attachment Devices, of which the following is a specification.

The present invention relates to means for the attachment of carpets to staircases and has for its principal object to provide a construction which will be simple and effective.

Our invention also has for its object to provide means for facilitating the engagement and disengagement of the carpet by and from the device.

With these and other objects in view, this invention consists in the provision of a clamping device which substantially consists of two superposed parallel bars or rails for each stair of which one is stationary and the other movable and which are adapted to co-operate with each other so as to clamp the part of the carpet covering the stair.

It also consists in the provision of means for moving the movable bar or rail into and out of clamping position.

Our invention will be more fully understood by reference to the accompanying drawing in which similar reference characters denote corresponding parts, and in which

Figure 1 is a front view of a part of a staircase equipped for each step with my new clamping device; Fig. 2 is a longitudinal section on line 2—2 of Fig. 1; Fig. 3 is a side view of the bottom stair; Fig. 4 is an opposite side view of the same bottom stair; Fig. 5 is a section on line 5—5 of Fig. 1; Fig. 6 is a section of bottom stair on line 6—6 of Fig. 1; Fig. 7 is a section on line 7—7 of Fig. 1, and Fig. 8 is a section on line 8—8 of Fig. 3.

In the present example we have shown our device applied to a staircase in which the bottom riser is curved longitudinally while all other risers are rectangular. In such case the clamping device for the bottom riser while in principle identical with, but for reasons that will be hereinafter given, constructionally somewhat different from the devices used for the rectangular steps.

We shall refer first to the construction of the device for ordinary rectangular risers.

10 denotes the rectangular treads of which only one is shown and 11 denotes the curved bottom tread of the staircase. The carpet C 60 is adapted to be laid from the top down, although it may be laid in reverse direction, covering each individual riser in the usual way.

The clamping devices and the means for 65 operating the same are adapted to be hidden behind the carpet. Each clamping device is composed of two superposed longitudinal members made in form of angle bars or L-shaped rails 12, 13 arranged parallel to each other. The L bar 13 is fixed with its horizontal side 13' to the upper face of the riser below, as 11 in the example shown, by means of screws 14 or the like so that the free edge of said side bears against the adjacent riser 10' and the vertical side 13² of said bar runs parallel to said riser 10' and is located at some distance from the latter forming a free space 15.

The rail or bar 12 is movably suspended 80 above the rail 13, the vertical side 12' of said rail being adapted to slidably bear on the riser 10' while the other side 12² of said rail or bar extends forwardly and downwardly not quite to the inner face of the 85 vertical side 13² of the lower rail. This movable rail 12 is adapted in open position to be so far raised from the lower rail as to form a slot like opening 16.

The carpet C covering the staircase is 90 adapted to extend over the clamping devices concealing the latter. The vertical fold c' of the carpet C covering the riser 10' is folded upon itself near the lower rail 13 to form a flap c² which is folded over the 95 upper edge of the side 13² of said rail and passed through the slot like opening 16 into the space 15. When the upper rail 12 is moved downwardly its forward edge in cooperation with the vertical side 13² of the 100 lower rail clamps the flap c² and thereby secures the carpet in position.

The forwardly and downwardly projecting side 12² of the upper rail 12 is preferably arranged at an obtuse angle to the side 12' so as to slant downwardly, in order to safeguard against accidental unlocking.

The movable rail 12 will not only clamp the carpet as stated, but when the carpet is led from the top down, it will on engaging 110

the flap c^2 and as it is moved into clamping position draw the vertical fold c' taut.

For the movable suspension of each rail 12 we provide a plurality of uniformly long arms 17 which are fulcrumed by means of screws 18 or the like to the riser 10' of each step 10, all fulcrums of the arms 17 being arranged in a single horizontal plane. The lower ends of the arms 17 are pivotally connected to the vertical side 12' of the rail 12 as at 19. At one end of the rail 12 we provide means for operating the same. These means, according to the present embodiment of my invention, consist of a lever 20 which is fulcrumed to the riser 10' at 21, the fulcrum lying in the same plane as the fulcrums of the arms 17. At the outer side of the lever we provide a swinging member 22 in form of a plate or the like which is centrally fulcrumed to the riser 10' in the same plane as the fulcrums 21 and 18 and which is formed in its center with a square pin 23 for the engagement of a key (not shown). The member 22 is connected by two parallel links 24 to the lever 20, the connecting points 25, 26 being located one above and the other below the fulcrum 21 of the lever 20. Thus by swinging the member 22 in one or the opposite direction, the lever 20 will be turned to lift or lower the bar or rail 12, relative to the lower rail 13. At one end of the rail 12 a stop 27 is provided which will limit the extent of the downward movement of the rail 12.

35 Referring now to the curved bottom riser 11 the superposed rails 28, 29 must be curved in conformity with the curvature of the tread to enable the clamping of the carpet around the curved corners of the step. The rail 28 is fixed to the floor adjacent to the step by screws 30 or the like just like the rail 13. The upper rail 29 is movably suspended from the riser 11'. The suspension means in this case comprise an auxiliary rail or band 31 curved around and parallel to the riser 11' and a plurality of toggle links 32 pivoted to said band at 33. These toggle links at their upper ends are fulcrumed at 34 to the riser 11' and at their lower ends at 35 to the rail 29. Two or more of the toggle links are also connected at their lower pivots to crank arms 36 which are fulcrumed to the riser 11' at points 36' intermediate the rail 29 and band 31. Each end of the auxiliary band 31 is pivotally connected to a crank arm 37 carried by a bracket 38 fixed to the staircase as at 39. The fulcrum of each crank arm 37 is extended forwardly and formed to a square 37' for the engagement of a key or the like for the manipulation of the rail 29.

The provision of the band 31 and the toggle links 32 for the rail 11 has been found necessary in order to facilitate the transmission of movement to the rail 29 around

the corners of the step 11. Inasmuch as the band 31 has the tendency to bulge forwardly when a push action is exerted on the toggle links 32 we found it advantageous to provide an operating arm for each end of the rail. This enables us to move the rail into and out of clamping position by turning the operating crank 37 at one end or that on the opposite end of the rail 29 to exert a pull action on the links 32.

Of course, the device may be modified in various ways without departing from the principle of our invention and we, therefore, do not wish to restrict ourselves to the details shown and described.

What we claim and desire to secure by Letters Patent is:—

1. In a device for attaching a carpet to a riser of a staircase, a stationary rail fixed to and extending longitudinally of and near the foot of the riser and a second member parallel to said stationary member and capable of moving parallel to itself to clamp the carpet between itself and said stationary member.

2. In a device for attaching a carpet to a staircase, a stationary member and movable member for each riser, coöperating with each other to clamp the carpet, and means for moving each movable member parallel to itself and said stationary member, said members and means being concealed behind the carpet.

3. In a device for the attachment of a carpet to a staircase, a pair of parallel members at the foot of each riser of which one member is fixed and the other movable and means for moving said movable member parallel to itself.

4. In a device for the attachment of a carpet to a staircase, a stationary rail and a movable rail for each riser adapted to co-operate with each other to clamp the carpet, a plurality of swinging arms carrying said second rail and means for moving said rail.

5. A device for the attachment of a carpet to a curved riser of a staircase comprising a curved clamping rail embracing said riser and means for moving the same parallel to itself.

6. A device for the attachment of a carpet to a curved riser of a staircase, comprising a pair of curved rails embracing said riser and of which one is fixed and the other movable, a plurality of swinging members carrying said movable rail and whereby said rail is movable parallel to itself and means at each end of said movable rail for lifting and lowering the latter.

7. A device of the character described, comprising a pair of superposed parallel clamping rails of which one is movable parallel to itself.

8. A device of the character described, comprising a pair of parallel L rails extend-

ing longitudinally of a step and of which one is movable parallel to itself.

9. A device of the character described, comprising a rail movable parallel to itself 5 and a key operated means for moving said rail.
10. In a device of the character described, a carpet engaging member movable vertically parallel to itself and a key operated 10 means at each end thereof to move said member into and out of operating position.

11. In a device of the character described, a curved vertically movable carpet engaging member, a plurality of toggle links carrying 15 said member and means at each end of the latter for swinging said links so as to raise

and lower said member into and out of engaging position.

12. In a device of the character described, a curved vertically movable carpet engaging 20 member, a plurality of connected toggle links carrying said member and means at each end of the latter for swinging said links so as to raise and lower said member into and out of engaging position. 25

In testimony whereof we affix our signatures in presence of two witnesses.

WALTHER GLOOR.

LOUIS HAACK.
